UNITED STATES PATENT OFFICE.

FRED C. BOYD, OF NEW HAVEN, CONNECTICUT, ASSIGNOR TO THE FARADAY CO., OF NEW HAVEN, CONNECTICUT, A CORPORATION.

DESIGN FOR AN ELECTRIC HEATER.

54,887.

Specification for Design. Patented Apr. 20, 1920.

Application filed October 13, 1919. Serial No. 330,496. Term of patent 14 years.

To all whom it may concern:

Be it known that I, FRED C. BOYD, a citizen of the United States, residing at New Haven, in the county of New Haven and the State of Connecticut, have invented a new, original, and ornamental Design for an Electric Heater, of which the following is a specification, reference being had to the accompanying drawing, forming part thereof.

Figure 1 is a front view of an electric heater showing my new design.

Fig. 2 is an end view of the same.

I claim:

The ornamental design for an electric heater as shown.

FRED C. BOYD.
